CLAIM

The ornamental design for panniers, as shown and described.

DESCRIPTION

FIG. 1 is a front elevational view of panniers, showing my new design;

FIG. 2 is a top plan view thereof;

FIG. 3 is a bottom plan view thereof;

FIG. 4 is a rear elevational view thereof;

FIG. 5 is a left side elevational view thereof;

FIG. 6 is a fragmentary exploded perspective view thereof;

FIG. 7 is a fragmentary perspective view thereof, showing a pannier in its opened condition; and,

FIG. 8 is a perspective view thereof, showing the panniers in use on a motorcycle.

The right side view of the panniers is a mirror image of the left side elevational view.

The broken line showing of the rear of a motorcycle in FIG. 8 is for illustrative purposes only and forms no part of the claimed design.
